UNITED STATES PATENT OFFICE

156,556

DRINK MIXER

Robert P. Pierce, Chicago, Ill.

Application September 3, 1947, Serial No. 141,178

Term of patent 14 years

(Cl. D2—3)

To all whom it may concern:

Be it known that I, Robert P. Pierce, a citizen of the United States, residing at Chicago, Cook County, Illinois, have invented a new, original, and ornamental Design for a Drink Mixer, of which the following is a specification, reference being had to the accompanying drawing, forming a part thereof:

Fig. 1 is a front elevational view of a drink mixer, showing my new design;

Fig. 2 is a fragmentary side elevational view with portions broken away to show the clapper member; and

Fig. 3 is a top plan view thereof.

The dominant features of my design reside in the portions shown in full lines.

I claim:

The ornamental design for a drink mixer, substantially as shown and described.

ROBERT P. PIERCE.
